CLAIM

I claim the ornamental design for a light, as shown and described.

DESCRIPTION

FIG. 1 is a front perspective view of a light showing my new design.

FIG. 2 is a front elevational view thereof.

FIG. 3 is an elevational view taken from the left side in FIG. 2.

FIG. 4 is an elevational view taken from the right side in FIG. 2.

FIG. 5 is a top plan view thereof.

FIG. 6 is a bottom plan view thereof.

FIG. 7 is a rear elevational view thereof.

FIG. 8 is a front perspective view thereof similar to FIG. 1 but including a clock in dash lines for illustrative purposes.

FIG. 9 is a rear perspective view showing the rear side of the clock in dash lines for illustrative purposes.

FIG. 10 is a front perspective view of an alternate embodiment of the light. FIG. 10 is the same as FIG. 1 except it includes the front side of a clock; and,

FIG. 11 is a rear perspective view of the embodiment of FIG. 10. FIG. 11 is substantially the same as the rear elevational view shown in FIG. 7 except it includes the rear side of a clock.
